(57) **CLAIM**

We claim the ornamental design for an architectural panel with sun palms, as shown and described.

DESCRIPTION

FIG. 1 is a perspective view of an architectural panel with sun palms, showing our new design

FIG. 2 is a front view of the architectural panel with sun palms.

FIG. 3 is a back view of the architectural panel with sun palms.

FIG. 4 is a left side view of the architectural panel with sun palms.

FIG. 5 is a right side view of the architectural panel with sun palms.

FIG. 6 is a top view of the architectural panel with sun palms; and,

FIG. 7 is a bottom view of the architectural panel with sun palms.

The broken lines adjacent to the shaded portions of the design depict the bounds of the claim and all other broken lines depict environmental subject matter. All broken lines form no part of the claim.
